UNITED STATES PATENT OFFICE

JACOB FREDERICK SCHOELLKOPF AND HOARD LEE, OF DALLAS, TEXAS

TRUNK

Application filed August 11, 1930. Serial No. 474,380.

This invention relates to automobile trunks and the principal object of the invention is to provide a trunk of this character capable of being extended when required for larger carrying capacity.

Another object of the invention is to provide a trunk for automobiles which when extended for larger carrying capacity can be entirely covered and locked, the cover being of a novel form of construction for bringing this about.

A further object of the invention resides in the unique manner of shifting the movable section of the trunk to a position whereby the trunk is enlarged and enabling the shifted portion to maintain a horizontal position.

A still further object of the invention resides in the means for providing greater strength of the trunk when the same is extended and for greatly strengthening the trunk generally.

With the above and other objects in view, the invention will be fully understood from a perusal of the following detailed description, taken in connection with the accompanying drawings, and wherein:

Figure 1 represents a side elevation of the rear portion of an automobile and illustrating the improved trunk in position thereon, the broken lines indicating its extended position.

Figure 2 is an enlarged front elevational view of the trunk when extended and with the lid raised and part folded back, part of the trunk being broken away for convenience.

Figure 3 represents a transverse vertical sectional view of Figure 2, the view being taken along the line 3-3 of Figure 2.

Figure 4 is a side elevational view of the trunk, reduced in size, showing the trunk fully extended and the entire cover in closed and locked position, part of the trunk being broken away for convenience, and

Figure 5 is a sectional detailed view, enlarged, the view being taken along the line 5-5 of Figure 3.

Having a more detailed reference to the drawings, the trunk consists of a stationary or fixed member A, a movable member B and a main lid 3. The member A is rigidly attached to a support 4, or the like, carried by

the automobile, and consists of the rear wall 5, side walls 6 and bottom wall 7. The member B consists of the front wall 8, side walls 9 and bottom wall 10. It will be apparent from Figures 3 and 4 that the top edges of the side walls 6 are cut on a slight incline and likewise the side walls 11 of the lid 3 are cut at a slant. This arrangement provides a cavity or recess for the purpose of enabling an extensible lid 12 to be moved out of the way when the trunk is not extended.

The extensible lid 12 is so constructed that when extended it will provide a cover for the section B, as shown in Figure 4, and in collapsible position in Figure 3, where in the latter position it lies within the recess of the lid 3. In forming a connection between the main lid 3 and the extensible lid 12, there are provided the angular bars 36 (shown more clearly in Figure 2) one end of these bars being pivoted at 37 to the main lid 3, and their opposite ends likewise connected at 38 to the extensible lid 12. The lid 12 can then be swung inwardly or outwardly from the recess in the lid 3 by the bars 36, and when in position underneath the lid 3, the hooks 39 receive the edge 40 of the lid 12, in the manner shown in Figure 3. Then the extensible lid is fastened in position by a catch 41.

Members 15 are provided for fastening the extensible lid 12 to the front wall 8 of the member B. These members form a connection with the lock plates 17 and when the connection is made a key is inserted into the key hole 18 to lock the parts. Similar members 19 are used when the lid 12 is not in use. The main lid 3 is also provided with the members 20, hinged to the side walls 6 and to the cover or lid 3 to limit its backward movement.

Referring to Figure 3, the means for connecting the member B to the member A is provided by the links 21 and 22, pivoted at the points 23 and 24 to the member B and at 25 and 26 to the member A. For the purpose of strengthening this pivotal connection, there is provided a bar 27, lying vertically and against the side walls 6 of the member A. Also the forward edges of the side walls 6 are flanged as at 28, see Figure 5, and the links 22 are extended somewhat beyond

- their pivotal points 24 and seat in these flanges when the member B is extended. Due to this manner of pivotally connecting the two members A and B together, the member B is permitted to retain its horizontal position at all times. Thus it will be apparent from the broken-line position of the member B, in Figure 3, that this member when shifted to extended position, or moved 10 backwardly into the member A, rises vertically, is then moved horizontally and finally comes to rest vertically. When in its fully extended position, the angular lip or edge 30 of the extensible lid 12 laps over the flange 32 of the wall 8. The rearward edge 40 of the extensible lid 12 is then disposed inside the lid 3 and forms a tight joint with the forward edge of the lid 3, as clearly shown in Figure 4.
- 20 The invention is capable of some modifications in structure, such as would be within the range of equivalents and in keeping with the appended claims.
- What is claimed as new is:
- 25 1. An automobile trunk comprising a stationary trunk member with a lid and a shiftable trunk member, said members being pivoted together by links, one of said links having one end connected to the lower edge of the side wall of the shiftable trunk member; a vertically-disposed bar secured to the inner side wall of the stationary trunk member, the opposite end of said link being pivoted to the lower end of said bar, an upper and 30 similarly disposed and similarly connected link at the upper portion of the trunk, the two links constituting a pair, one pair of links for each side of the trunk; the forward edges of the side walls of the stationary member carrying inwardly directed flanges wherein the outer ends of the upper links seat when the members are in extended position.
- 40 2. An automobile trunk as claimed in claim 1, wherein said lid is hinged to said stationary trunk member and has an extensible lid connected to the main lid, said connection being established by angular bars, one end of each of said bars being pivotally connected to said main lid and the opposite end pivoted to said extensible lid, whereby the extensible lid can be moved within the main lid when not in use, and means for holding the extensible lid in non-extended position.
- 45 3. In testimony whereof we affix our signatures.
- JACOB FREDERICK SCHOELLKOPF.
HOARD LEE.
